US0D1051739S

(12) **United States Design Patent** (10) **Patent No.:** **US D1,051,739 S**
(45) **Date of Patent:** **** Nov. 19, 2024**

(54) **METAL DETECTION PROBE**

(71) Applicant: **Ebinger Prüf- und Ortungstechnik GmbH**, Cologne (DE)

(72) Inventors: **Oliver Bartsch**, Cologne (DE); **Irene Ebinger**, Cologne (DE); **Ingeborg Ebinger**, Cologne (DE)

(**) Term: **15 Years**

(21) Appl. No.: **35/516,699**

(22) Filed: **Mar. 1, 2023**

(80) **Hague Agreement Data**

Int. Filing Date: **Mar. 1, 2023**

Int. Reg. No.: **DM/227505**

Int. Reg. Date: **Mar. 1, 2023**

Int. Reg. Pub. Date: **Mar. 24, 2023**

(51) **LOC (14) Cl.** **10-04**

(52) **U.S. Cl.**

USPC **D10/47**

(57) **CLAIM**

The ornamental design for a metal detection probe as shown and described.

DESCRIPTION

The patent or application file contains at least one drawing executed in color. Copies of this patent or patent application publication with color drawing(s) will be provided by the Office upon request and payment of the necessary fee.

1.1 : Perspective

1.2 : Front

1.3 : Left

1.4 : Top

Reproduction **1.1**: perspective view; reproduction **1.2**: front view; reproduction **1.3**: left view; reproduction **1.4**: top view.

The elements of the design lined in red form no part of the claimed design.

1 Claim, 4 Drawing Sheets
(4 of 4 Drawing Sheet(s) Filed in Color)
